(57) **CLAIM**

The ornamental design for a roof of an agricultural work vehicle, substantially as shown and described.

DESCRIPTION

FIG. 1 is a front perspective view of a roof of an agricultural work vehicle;

FIG. 2 is a rear perspective view of the roof;

FIG. 3 is front perspective view of the roof;

FIG. 4 is a rear perspective view of the roof;

FIG. 5 is a left side view of the roof;

FIG. 6 is a right side view of the roof;

FIG. 7 is a front view of the roof;

FIG. 8 is a back view of the roof;

FIG. 9 is a top view of the roof; and,

FIG. 10 is a bottom view of the roof.

Phantom lines, where utilized, are for illustrative purposes only and form no part of the claimed design.

1 Claim, 8 Drawing Sheets
